UNITED STATES PATENT OFFICE.

DANIEL PASTON, OF BROOKLYN, NEW YORK.

DESIGN FOR A SHAWL OR THE LIKE.

Application filed February 3, 1925. Serial No. 12,247. Term of patent 8½ years.

To all whom it may concern:

Be it known that I, DANIEL PASTON, a citizen of the United States, residing at Brooklyn, in the county of Kings and State of New York, have invented a new, original, and ornamental Design for Shawls or the like, of which the following is a specification, reference being had to the accompanying drawing, forming a part thereof.

The figure is a plan view of a shawl, showing my new design.

The six pointed star feature appearing in detail at certain points in the shawl, as shown in the drawing, is repeated throughout the entire area of the shawl.

I claim:

The ornamental design for a shawl or the like, as shown and described.

DANIEL PASTON.
